The ornamental design for a boxing game vest, as shown and described.

DESCRIPTION

FIG. 1 is an isometric view of boxing game vest showing my new design;

FIG. 2 is a front elevational view of FIG. 1;

FIG. 3 is a rear elevational view of FIG. 1

FIG. 4 is a right elevational view of FIG. 1;

FIG. 5 is a left side elevational view of FIG. 1;

FIG. 6 is a top plan view of FIG. 1;

FIG. 7 is a bottom plan view of FIG. 1;

FIG. 8 is a front elevation operational view with straps of FIG. 1; and,

FIG. 9 is a rear elevation operational view with straps of FIG. 1.

The broken lines showing of straps and buckles, in FIGS. 8 and 9, illustrate environmental structure and form no part of the claimed design. The remaining broken lines in the drawings depict portions of the boxing game vest that form no part of the claimed design.
